Primary Examiner — Darcey E Gottschalk

CLAIM

The ornamental design for a water bottle lid, as shown and described.

DESCRIPTION

FIG. 1 is a perspective view of a water bottle lid showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the water bottle lid where the water bottle lid is in a first configuration of use;

FIG. 10 is a perspective view of the water bottle lid where the water bottle lid is in a second configuration of use;

FIG. 11 is a perspective view of the water bottle lid where the water bottle lid is in a third configuration of use; and,

FIG. 12 is a front elevational view of the water bottle lid shown in FIG. 9.

The broken lines in the drawings depict portions of the water bottle lid that form no part of the claimed design.

1 Claim, 12 Drawing Sheets
